UNITED STATES PATENT OFFICE.

RUSSELL M. COOK AND BENNETT GROTTA, OF TAMAQUA, PENNSYLVANIA, ASSIGNORS
TO ATLAS POWDER COMPANY, OF PHILADELPHIA, PENNSYLVANIA, A CORPORA-
TION OF DELAWARE.

COMPOSITION FOR DETONATORS.

1,406,977.

Specification of Letters Patent. Patented Feb. 21, 1922.

No Drawing.

Application filed September 25, 1920. Serial No. 412,812.

To all whom it may concern:

Be it known that we, RUSSELL M. COOK, and BENNETT GROTTA, citizens of the United States of America, residing at Tamaqua, in 5 the county of Schuylkill and State of Pennsylvania, have invented certain new and useful Improvements in Compositions for Detonators, of which the following is a specification.

10 Our invention relates particularly to an improvement in compositions used for detonating explosive charges, such as dynamite or gelatin.

We have discovered that hexanitrodiphenylamine when mixed with such primary detonating compounds as mercury fulminate or lead azide, and then pressed into shells which are used for blasting caps, forms a 15 powerful detonating composition, for when 20 the composition is ignited, as by means of a safety fuse, it detonates violently and with sufficient power to cause the detonation of dynamite. A suitable mixture is 90 parts mercury fulminate and 10 parts hexanitrodiphenylamine, or 90 parts lead azide and 10 parts hexanitrodiphenylamine.

25 Hexanitrodiphenylamine may also be used as the main charge of the blasting cap or electric blasting cap, with a primary detonating composition such as lead azide, mercury fulminate or mercury fulminate mixed with potassium chlorate, or other primary detonating composition. As an example, six 30 grains of hexanitrodiphenylamine may be loaded into a shell such as is used for blasting caps and pressed in place; seven grains of a mixture of 90 parts mercury fulminate and 10 parts potassium chlorate may be placed on top of the hexanitrodiphenylamine 35 and pressed in place; and the charge may 40 then be covered with an inverted capsule, if desired. The blasting caps so made can be ignited by the flame from a safety fuse in the usual way, and will detonate with great violence and sufficient power to cause the 45 detonation of dynamite.

50 While we have given specific examples of the use of hexanitrodiphenylamine in detonator compositions, it is to be understood that our invention is not limited to any particular detonator composition nor to any specific methods of use in blasting or other caps, but that we desire to claim in the 55 broadest manner the use of hexanitrodiphenylamine in detonator compositions.

Having described our invention, what we claim is:

1. A detonator composition consisting of a primary detonating compound and hexanitrodiphenylamine. 60

2. A detonator composition containing as an ingredient hexanitrodiphenylamine.

3. A blasting cap charge comprising a primary detonating compound and hexanitrodiphenylamine. 65

4. A blasting cap charge comprising mercury fulminate and hexanitrodiphenylamine.

5. A blasting cap charge comprising mercury fulminate 90 parts and hexanitrodiphenylamine 10 parts. 70

6. A detonating charge consisting of hexanitrodiphenylamine and a primary detonating compound and potassium chlorate.

7. A primer composition for explosives comprising hexanitrodiphenylamine. 75

8. A primer composition comprising hexanitrodiphenylamine and a primary detonating compound.

9. A primer composition comprising hexanitrodiphenylamine, a primary detonating compound and potassium chlorate. 80

10. A detonator composition for explosives comprising a main charge of hexanitrodiphenylamine and a primer containing fulminate of mercury. 85

11. A detonating composition for explosives comprising a main charge of hexanitrodiphenylamine and a primer containing a mixture of fulminate of mercury and potassium chlorate. 90

12. A detonating composition for explosives comprising a main charge of hexanitrodiphenylamine with a primer, consisting of a mixture of hexanitrodiphenylamine, potassium chlorate and fulminate of mercury. 95

13. A detonator composition for explosives comprising hexanitrodiphenylamine, fulminate of mercury and potassium chlorate.

14. A primer composition for explosives comprising hexanitrodiphenylamine, fulminate of mercury and potassium chlorate. 100

In testimony whereof we affix our signatures in the presence of two witnesses.

RUSSELL M. COOK.
BENNETT GROTTA.

Witnesses:

BENJAMIN C. BEDDALL,
